UNITED STATES PATENT OFFICE.

WILLIAM H. LERCH, OF CHICAGO, ILLINOIS, ASSIGNOR TO EUGENE DIETZGEN COMPANY, OF CHICAGO, ILLINOIS, A CORPORATION OF ILLINOIS.

DESURFACER.

1,222,875.

Specification of Letters Patent. Patented Apr. 17, 1917.

Application filed June 9, 1916. Serial No. 102,672.

To all whom it may concern:

Be it known that I, WILLIAM H. LERCH, a citizen of the United States, residing at Chicago, in the county of Cook and State of Illinois, have invented a certain new and useful Improvement in Desurfacers, of which the following is a specification.

My invention relates to desurfacers for removing the gloss from tracing linen and the like. It will be understood by those skilled in the art that tracing linen or tracing cloth, as it comes from the dealer, has a high gloss or glaze which prevents the drawing ink from flowing over it freely and evenly. Hence, it is the custom for draftsmen, before using the linen, to remove this gloss by rubbing chalk or other abrasive powder upon its surface. Some draftsmen simply use their fingers for the purpose, while others use a rag or whatever may come to hand. This practice is hardly neat, to say the least, and does not obtain the best or most uniform results, and the object of my invention is to provide means whereby an abrasive powder may be applied to and rubbed over the surface of tracing linen with neatness, thoroughness and despatch. Another object of my invention is to provide means whereby the amount of abrasive powder used to cover a given surface may be reduced to a minimum.

I accomplish my objects by the mechanism illustrated in the accompanying drawings, in which—

Figure 1 is a perspective view of my device in use.

Fig. 2 is an axial section of the device.

Fig. 3 is a top plan view.

In the form selected to illustrate the invention, the receptacle 1 is designed to contain the abrasive powder, and is preferably in the form of a cylindrical can about 2 inches in diameter—this diameter being convenient for the grasp of the average user.

The receptacle has what is known as a "shaker" top; that is, the top 2 of the receptacle is apertured and has fitting over it a cap 3, which is similarly apertured. Said cap is rotatable, so as to bring the apertures into and out of register. In the best form,

the cap comes partway down the sides, so as to furnish an annular surface which may be grasped by the user for rotating the cap. By preference this annular flange 3^a is beaded at the point 3^b to interfit with a corresponding beading at the point 1^a of the receptacle. The top and cap are convex upward, or dome-shaped.

A pad 4 of felt is secured to the top of the cap by gluing or otherwise and rotates with the cap. It has a central circular opening 5.

In operation, when the draftsman wishes to prepare the linen for use, he grasps the side flanges of the cap in the fingers of one hand and the can or receptacle in the other and rotates the cap until the apertures are in register. He then inverts the device over the tracing linen, as shown in Fig. 1, whereupon some of the powder drops onto the linen within the circle inclosed within the pad. He then moves the device back and forth over the surface of the linen, and no matter which way he goes, the powder, being surrounded by the pad, will be brushed over by the pad. In other words, the user does not need to take any particular care to rub where the powder is, for the powder will feed down into a space inclosed by the pad and hence will be acted upon by the pad regardless of the direction in which the device is moved. If the user finds that enough powder has been deposited before the entire surface of the linen has been treated, he will rotate the lid to close the apertures, after which he continues to rub the surface of the linen until the gloss has been completely removed.

As a result of my construction the receptacle itself becomes the handle for manipulating the pad, and as the cap and pad are both dome-shaped, the operator may easily and certainly work close up to the edges of the linen as well as toward the center.

Having thus described my invention, what I claim as new and desire to secure by Letters Patent, is:—

A desurfacer for tracing linen, consisting of a receptacle having a top and bottom, said top being convex and provided with per-

forations, a cover rotatably mounted on the top end of the receptacle and provided with perforations adapted to be moved into and out of registration with the perforations in the top end of the receptacle, and an abrading pad fixed on the cover with its rubbing surface conforming to the convexity of the

top end of the receptacle and having a central opening therein the wall of which surrounds the perforations in the cover.

10

In witness whereof, I have hereunto subscribed my name.

WILLIAM H. LERCH.
